Frautzsch & Richards
ATTORNEYS.

UNITED STATES PATENT OFFICE.

FREDERICK A. FELDKAMP, OF NEWARK, NEW JERSEY.

ELECTRIC FUSE.

Application filed August 26, 1921. Serial No. 495,648.

To all whom it may concern:

Be it known that I, FREDERICK A. FELDKAMP, a citizen of the United States, residing at Newark, in the county of Essex and State of New Jersey, have invented certain new and useful Improvements in Electric Fuses; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in fuse cartridges; and the invention has reference, more particularly, to a novel construction of renewable or refillable fuse cartridge.

The invention has for its principal object to provide a construction of renewable or refillable fuse cartridge adapted to greatly simplify the method of renewing blown fuses, whereby the operative manipulations required are reduced to a minimum. To this end I provide a novel form of external shell or container for holding one or more insert or refill fuse cartridges of substantially conventional form; the external shell or container being so constructed that the act of inserting a new insert or refill fuse cartridge into operative relation thereto, automatically expels the previously blown fuse cartridge.

A further object of the invention is to provide a novel construction of permanent external shell or container, which permits the use of inserts or refills made in conventional fuse cartridge form, but which, by reason of their inclosure within said shell or container, may be made of cheaper materials and smaller in size, so that the loss consequently on the blowing and destruction of the same is greatly reduced.

A still further object of the invention is to provide an outer shell or container of regulation size to fit standard sizes of clips, which can be used over and over again, and which is not subjected to the destructive and deteriorating effects of the electric arc consequent upon the blowing of a fuse, since the said arc is produced only within the insert or refill cartridge. It thus follows that said external shell or container is not subject to high heat every time a fuse blows, as is the case in refillable cartridges constructed to receive only a drop out or refill

fuse link or element, and consequently the shell or container is enabled to render long service, without danger of disruption due to the weakening of its fibre walls, while at the same time it serves to confine and reinforce the insert or refill fuse cartridge or cartridges which it is adapted to enclose.

Other objects of this invention, not at this time more particularly enumerated, will be clearly understood from the following detailed description of the same.

The invention is clearly illustrated in the accompanying drawings, in which:—

Figure 1 is a side elevation of one form of my novel removable fuse cartridge; Figure 2 is a longitudinal section of the external shell or container, showing an insert or refill fuse cartridge operatively associated therewith, the latter being shown in elevation; Figure 3 is a fragmentary longitudinal section, similar to that shown in Figure 2, but with the insert or refill fuse cartridge removed; and Figure 4 is a cross section taken on line 4—4 in said Figure 3.

Figure 5 is a longitudinal section of a slightly modified form of external shell or container adapted to hold a plurality of insert or refill fuse cartridges in such a manner that but one of the latter is in service at a time.

Figure 6 is also a longitudinal section of a further modified form of holder or container for a plurality of insert or refill fuse cartridges.

Figure 7 is a part side elevation and part longitudinal section of another form of external shell or container, embodying, however, the general principles of this invention.

Figure 8 is a fragmentary side elevation of the novel external shell or container equipped with knife-blade contacts; and Figure 9 is a longitudinal section and part elevation of the same, taken on line 9—9 in said Figure 8.

Similar characters of reference are employed in all of the hereinabove described views, to indicate corresponding parts.

Referring now to Figures 1 to 4 inclusive, the embodiment of my invention therein shown, comprises an external shell or container 10, which is made of fibre or other suitable non-conducting or insulation material, and which is tubular in form, having at each end, suitably secured thereto, by rivets 11, or in any other convenient manner, me-

tallic end ferrules or contact caps 12, provided in their end walls with openings 13 of a diameter substantially conforming to the internal diameter of the shell or container 10. Arranged within each ferrule or contact cap 12 is a contact-sleeve 14 having at its inner end an annular enlargement 15 which engages the inner surface of the ferrule or cap 12, and which is secured to the latter by solder or other fastening means, whereby the same is both mechanically and electrically connected therewith. Each sleeve is provided with slits 16 extending longitudinally inward from the free end 15 thereof, thus rendering the sleeve yieldingly expansible for purposes presently to be described. The reference character 17 indicates an insert or refill fuse cartridge of conventional construction and form, whereby the same is adapted to enclose a fuse element 18 extending between and electrically connected with the end contact caps 19 thereof. This insert or refill fuse cartridge 17 is made in proper dimensions, so that the same 20 may be inserted endwise through an open end of the external shell or container to move telescopically thereinto, and so that, when in place, its respective contact caps 19 are engaged by the contact-sleeves 14, thereby electrically connecting the insert or refill fuse cartridge with its fuse element 18 between the contact ferrules 12 of the shell or container 10. In order to assure a good electrical contact between the contact sleeves 14 and the contact caps 19 of the insert or refill fuse cartridge, the former are normally made slightly smaller in diameter than the diameter of said contact caps 19, and then provided with the slits 16 so that they will expand as the contact caps 19 enter the same, and will thereupon huggingly embrace the contact caps. The said external shell or container 10 with its end ferrules 12, is designed to possess the outside dimensions of a standard fuse-cartridge of any given size and capacity to which it is to correspond, and consequently will fit corresponding clips for holding the same in circuit. The insert or refill cartridge 17 may be made of lighter and smaller sized and cheaper material, but with a fuse element of proper capacity.

When the novel fuse cartridge, consisting of the combined external shell or container 10 and insert of refill fuse cartridge 17, is in service, the current passes through one ferrule 12, contact sleeve 14, and end cap 19 into and through the fuse element 18, and thence through the opposite end cap 19, contact sleeve 14 and out through the opposite ferrule 12.

When the fuse element 18 blows, the external container or shell 10 is removed from the clips, and a new insert or refill fuse cartridge is taken and inserted into one end 65 of the container or shell 10 to pass thereinto

for proper enclosure therein. This operation forces the blown fuse cartridge out of the opposite end of the container or shell, so that it will be apparent that the one operation required to insert a new insert or refill fuse cartridge, automatically operates to expel the old or blown fuse cartridge from the external container or shell, thus greatly simplifying the method and manipulation required to renew the device for further service, and eliminating all necessity for take-apart operations generally required when using the heretofore known type of refillable fuse cartridges.

Referring now to Figure 7, I have shown therein a type of my novel renewable fuse cartridge, which involves a slight modification of the construction of the external container or shell. In this construction I eliminate the contact-sleeves 14, and in place thereof I strike out of the walls of the ferrules 12 inwardly depressed fingers or contact arms 20, which electrically engage and mechanically embrace the end caps 19 of the insert or refill cartridge 17, when the latter is operatively associated with the external container or shell. This construction is very cheap, and for certain classes of fuses very satisfactory.

Referring now to Figure 5, I have shown a modified form of removable fuse cartridge, which embodies the general principles of this invention, but which involves some additional features, whereby the external container or shell is adapted to hold a reserve insert or refill fuse cartridge in addition to the insert or refill fuse cartridge which is active or in service. In this construction I provide a tubular external shell or container 21 made of a suitable insulating material, and provided at its respective ends with metallic end ferrules or contact caps 22, the latter being provided with the openings or passages 23 in their end walls. Arranged within the receiving end of said external shell or container 21 is a contact sleeve 24 which snugly fits the shell or container 21 and which is secured in place by rivets 25 or other suitable means, whereby the same, together with the adjacent end ferrule or contact cap 22, are fastened to the shell or container 21, and the sleeve 24 is at the same time electrically connected with said adjacent end ferrule or contact cap 22. Said contact sleeve 24 is provided at its outer end with an inwardly off-set annular gripping portion 26 having one or more longitudinal slits 27 to render the same expansible, and in like manner, said contact sleeve 24 is provided at its inner end with a similar inwardly off-set annular gripping portion 28, which is also provided with one or more longitudinal slits 29 to render the same expansible. Said contact sleeve 24 is of a length adapted to position said inner gripping por-

tion 28 slightly beyond the center of the external shell or container 21. Arranged within the opposite or discharge end of said external shell or container 21 is a contact sleeve 30 secured to said shell or container 21 and to the adjacent end ferrule or contact cap 22 by rivets 31, or other suitable fastening means, which also serve to electrically connect the contact sleeve with said end ferrule 5 or contact cap. The outer end of said contact sleeve is provided with an inwardly offset annular gripping portion 32, which is provided with one or more longitudinal slits 33 to render the same expansible. With the 10 external shell or container thus constructed I may employ a plurality of insert or refill fuse cartridges. In the form illustrated in the drawing the same is arranged to receive two insert or refill fuse cartridges 34 and 20 35, which are arranged end to end so that the contact cap 34' of the cartridge 34 is embraced by the gripping portion 28 of the contact sleeve 24, and the opposite contact cap 34'' is embraced by the gripping portion 32 of the contact sleeve 30, while the outer contact cap 35' of the cartridge 35 is engaged by the gripping portion 26 of the contact sleeve 24, and is thus held against rearward displacement from the shell or container 21. With the cartridges 34 and 35 thus arranged, the former occupies an active or in service relation to the shell or container 21, while the latter occupies an inactive or short-circuit relation thereto. The electric current is passed from one end ferrule or contact cap 22 into the contact sleeve 24, thence passing into the contact cap 34' through the fuse of the cartridge 34 to the opposite contact cap 34'', and thence through 40 the contact sleeve 30 to the opposite end ferrule or contact cap 22 of the shell or container 21. It will thus be apparent that the cartridge 35 is short circuited by the contact sleeve 24 and remains inactive, while the cartridge 34 carries the current load. When the cartridge 34 blows and it is desired to replace the same, a new insert or refill cartridge is thrust against the outward end of the cartridge 35, causing the latter to move 45 longitudinally forward to an "in service position" while the new cartridge enters into reserve position within the shell or container 21 formerly occupied by said cartridge 35. This shifting of the cartridge 35 not only 50 carries the same to an "in service" position, but also serves to eject the blown cartridge 34 from the shell or container 21. The cartridge 35 now has its contact cap 35' engaged with the inner end of the contact sleeve 24, 55 while its contact 35'' is engaged with the contact sleeve 30 of the shell or container 21 thus bridging the current from the former to the latter. It will be evident that this construction of my novel refillable fuse cartridge offers a very advantageous arrange- 60

ment whereby a reserve refill fuse of proper capacity is always at hand. It will also be understood that the reserve fuse may be longitudinally shifted to active position by exerting endwise pressure thereon with any handy means in the absence of another insert or refill fuse cartridge. 70

Referring now to Figure 6, I have shown another form of the last above described type of my novel refillable fuse cartridge. In this form, I have an external shell or container 36 having the end ferrules 37, the latter having end walls 38 provided with the passages or openings 39. Extending into the receiving end of said shell or container 36 is a contact sleeve 40, having at its outer end an outwardly projected annular flange 41 which extends under and is soldered to or otherwise secured beneath the end wall of the adjacent end ferrule or contact cap 37, thus mechanically and electrically securing the contact sleeve to the latter. The inner end of said contact sleeve 40 is provided with longitudinal slits 42 to render the same expansible, while the body of the sleeve toward its outer end is likewise provided with slits 43, whereby an insert or refill cartridge will be embraced and gripped against displacement. Extending into the discharge end of said shell or container 36 is a second contact sleeve 44, also having at its outer end an outwardly projected annular flange 45 which extends under and is soldered to or otherwise secured beneath the end wall of the adjacent end ferrule or contact cap 37 thus mechanically and electrically securing the said contact sleeve to the latter. The inner end of said contact sleeve 44 is likewise provided with slits 46 to render the same expansible. Two insert or refill cartridges 47 and 48 are employed, the former occupying an "in service" position bridging the gap between the inner ends of the respective contact sleeves 40 and 44, while the latter occupies a reserve and short circuited position within the outer end of the contact sleeve 40. The method of manipulation and the advantages of this form of my refillable fuse cartridge are the same as already heretofore described in connection with the form shown in Figure 5 of the drawings. 100

Referring now to Figures 8 and 9 of the drawings, I have shown a means of applying knife-blade contacts to the external shell or container of my novel refillable fuse cartridge. The reference character 49 indicates the external shell or container provided with the end ferrules 50. Said end ferrules 50 are provided with suitably located outwardly projected studs 51. The reference character 52 indicates a metallic cap provided with a bayonet slot 53. The knife-blade contact 54 is secured to the end of said cap 52, preferably by rivet portions 55 which ex- 105 110 115 120 125 130

tend through the end wall of the said cap and through a copper disc 56 arranged within the cap, and adapted to provide a good electrical contact with the end ferrule 50 over which the cap is engaged. By thrusting the caps over the end ferrules and properly engaging their bayonet slots with the studs 51 of said ferrules, the knife-blades may be properly alined, and both electrically and mechanically secured to the shell or container 49 so as to be capable of quick detachment when removing and renewing the insert or refill fuse cartridges from said external shell or container.

15 I am aware that some changes may be made in the general arrangements and combinations of the various devices and parts of my present invention, without departing from the scope thereof as set forth in the 20 foregoing specification and as defined in the appended claims. Hence, I do not limit my present invention to the exact arrangements and combinations of the various devices and parts as described in said specification, nor 25 do I confine myself to the exact details of the construction of the said parts as illustrated in the accompanying drawings.

I claim:

1. A fuse cartridge, comprising a tubular 30 casing of insulating material having external metallic ferrules at its respective ends, said ferrules being open at their outer ends, internal annular contact sleeves respectively in fixed electrical engagement with said respective ferrules, said sleeves having expansible gripping portions, and a refill cartridge fuse of conventional form longitudinally movable into and out of said shell from either end thereof, said expansible gripping portions being adapted to engage the respective contact caps of said refill cartridge fuse to electrically connect the latter between said internal contact sleeves.

2. A fuse cartridge, comprising a tubular 45 casing having external contacts at its extremities, an internal contact element electrically connected with one external contact

of said casing to extend inwardly beyond the center of said casing interior, a second internal contact element electrically connected with the opposite external contact of said casing to extend inwardly but spaced longitudinally from the first memtioneed contact element, and a plurality of refill cartridge fuses of conventional form, one of the latter normally occupying an "in service" position electrically engaged with and between the opposed ends of said internal contact elements.

3. A fuse cartridge, comprising a tubular casing having external ferrules provided with outer open ends, an internal contact sleeve electrically connected with one contact ferrule, said sleeve extending inwardly through said casing beyond its central portion, a second internal contact sleeve electrically connected with the opposite contact ferrule, said second sleeve extending inwardly through said casing but spaced longitudinally from the first mentioned sleeve, means rendering the opposed ends of said sleeves expansible, and a plurality of refill cartridge fuses of conventional form movable endwise into and out of said casing, one of the latter normally occupying an "in service" position electrically engaged with and between the opposed ends of said sleeves.

4. A refillable fuse cartridge comprising a tubular external shell having open outer ends and external contact members and adapted to hold a series of refill cartridge fuses in alinement, and means upon said tube for maintaining one only, of said cartridge fuses in electrical contact with said external contact members.

In testimony, that I claim the invention set forth above I have hereunto set my hand this 23rd day of August, 1921.

FREDERICK A. FELDKAMP.
